BAR TOOL HOLDER

Bela B. Nevai, Dobbs Ferry, N.Y., assignor to Nevco
Wood Products Co., Inc., Yonkers, N.Y., a corporation of New York

Filed May 3, 1966, Ser. No. 2,141

Term of patent 14 years

(Cl. D44—29)

FIG. 1 is a perspective view of the bar tool holder, showing the present design;

FIG. 2 is a perspective view taken from the opposite side;

FIG. 3 is a top plan view of the bar tool holder;

FIG. 4 is an elevational view of the bar tool holder, illustrating the surface shown in FIG. 1; and

FIG. 5 is a side elevational view of the bar tool holder. I claim:

The ornamental design for a bar tool holder, as shown.
